CLAIM

The ornamental design for photography stand, as shown and described.

DESCRIPTION

FIG. 1 is a front, right and top perspective view of a photography stand showing my new design;
FIG. 2 is a rear, left and bottom perspective view thereof;
FIG. 3 is a front elevational view thereof;
FIG. 4 is a rear elevational view thereof;
FIG. 5 is a left view thereof;
FIG. 6 is a right view thereof;
FIG. 7 is a top plan view thereof;
FIG. 8 is a bottom plan view thereof;
FIG. 9 is an enlarged view of a portion labeled as 9 on FIG. 1; and,
FIG. 10 is an enlarged view of a portion labeled as 10 on FIG. 2.
The long dash-short dash broken lines depict enlargement boundaries that form no part of the claim.

1 Claim, 10 Drawing Sheets
